DISAPPEARING WATER BALLET DEVICE

Lottie Mayer Warfield and Kenneth B. Warfield,
Artesia, Calif.

Application December 19, 1933, Serial No. 703,098

10 Claims. (Cl. 272—26)

This invention relates as indicated to a device especially adapted for use in conjunction with a disappearing water ballet performance and more especially to means whereby the performers may be made to disappear below the surface of the water in a tank and made to reappear after having effected a change in costume or the like.

More specifically, this invention relates to apparatus whereby performers may disappear below the water level in a tank, remain out of sight for an appreciable length of time, i. e., longer than a normal person could stay under water, and then reappear either with their original or changed costume.

15 It is among the objects of our invention to provide a device for the accomplishment of the above-named ends by the employment of means characterized by simplicity of construction and manipulation.

20 It is another object of our invention to provide a device of the above described character which may be employed to accomplish the desired results with a minimum of hazard to the performers.

25 Other objects of our invention will appear as the description proceeds.

To the accomplishment of the foregoing and related ends, said invention, then, consists of the means hereinafter fully described and particularly 30 pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of an apparatus constructed in accordance with the principles of our invention; Fig. 2 is a front elevational view of the apparatus illustrated in Fig. 1; Fig. 3 is a transverse sectional view of a portion of the apparatus illustrated in Fig. 1 taken on a plane substantially indicated by the line 3—3; Fig. 4 is a sectional view similar to Fig. 3, but showing only a portion of Fig. 3 drawn to an enlarged scale and illustrating in dotted lines a second position of the lower portion of the inclined stairway; Fig. 5 is a fragmentary elevational view of a portion of the means employed for the purpose of adjustably supporting or collapsing the lower section of the inclined stairway illustrated in Figs. 3 and 4; and Fig. 6 is a fragmentary sectional view of a portion of the tank illustrated in Figs. 1 and 2,

showing more particularly the arrangement of the partition which extends across the tank.

Referring now more specifically to the drawings and more especially to Figs. 1 and 2, the apparatus constructed in accordance with the principles of our invention consists of a substantially cylindrical water-filled tank, generally indicated at 1. This tank may be constructed in any suitable fashion so as to hold water which normally rises to the line indicated at 2 in Fig. 2. The tank 1 may be conveniently constructed from a cylindrical shell open at both ends which is placed on the floor of a room or stage and then a canvas or other flexible water-tight liner having a closed bottom is placed within the shell and laterally confined thereby. This construction is characterized particularly by being portable which is one of the principal advantages of apparatus of this character.

Suitably vertically disposed ladders, generally indicated at 3, may be supported within the tank 1 whereby performers may rise out of the tank, should the occasion demand.

Supported by the vertically extending braces, generally indicated at 4, in Fig. 2, or by any other suitable means, are a plurality of platforms 5 and 6 and runways 7 which are arranged about the tank 1 to support the performers at the various elevations, most clearly illustrated in Fig. 2. Small platforms 8 may be provided adjacent the ladders 3 and preferably level with the top of the tank whereby performers emerging from the tank 1 by means of the ladder 3 may pass to the platforms 5 by means of stairs 9. Supported adjacent the platforms 5 are spring diving boards 10 which are supported in the usual manner and extend to the edge of the tank 1, whereby performers may dive into the tank.

Suitable overhead means (not shown) such as trapeze apparatus may be provided for performers giving a demonstration above the tank and diving from such trapeze into the tank.

As previously indicated, the principal object of this invention is to provide means whereby performers may pass below the surface of the water in the tank and apparently disappear for any desired length of time so that the performers may apparently stay below the level of the water for periods of time longer than that which an ordinary person might stay submerged. The apparatus also makes possible the changing or altering of costumes by the performers whereby the illusion of having changed costumes under water may be produced. The apparatus presently to be described for accomplishing these ends is

preferably positioned entirely within and above the tank 1.

As most clearly illustrated in Figs. 1 and 3, we provide an inclined stairway, generally indicated 5 at 11, which consists of an upper fixed section 12 and a lower movable section 13. The two sections 12 and 13 meet at approximately the water line 2 in the tank 1. The section 12 is rigidly supported by suitable means such as standards 10 14 and 15, the former, for convenience, being outside the tank and the latter being in the tank. As above indicated, it is within the contemplation 15 of our invention, however, to position the support 14 within or upon the tank, should this be desirable.

The lower section 13 is, at its upper end, pivotally secured to the upper section 12 by some suitable means such as a hinge 16, most clearly illustrated in Fig. 4. The lower end of the section 13 has a leg 17 pivotally secured thereto, which when the parts are in the position illustrated in full lines in Figs. 3 and 4, supports the lower end of the section 13 at a position above the bottom of the tank 1. The section 13, as illustrated in Fig. 3, terminates above the bottom of the tank for a distance sufficient to permit such section to move arcuately into the dotted line position illustrated in Fig. 4 without striking the bottom of the tank 1.

Links 18 and 19 interconnect the leg 17 and the standard 15 and a cable or rope 20 is attached to the link 19 whereby such link and those connected therewith may be actuated to move the stair section 13 from the full line to the dotted line position illustrated in Fig. 4 in the manner presently to be explained.

Assuming that the parts are in the position illustrated in full line in Fig. 4, the stair section 13 may be moved to the dotted line position illustrated in such figure by merely pulling on the rope or cable 20, which rope is, for convenience, carried to an operator's station, generally indicated at 21, underneath a fixed stair section 12. When the rope 20 is pulled upwardly, the link 19 is first moved about the axis of the hinge 22 in a counterclockwise direction, whereupon the link 18 will move about the axis of the hinge 23 in a clockwise direction with respect to such hinge. At the same time, the link 18 will move in a 50 clockwise direction about the axis of the hinge 24 which interconnects such link and the leg 17. This movement of the links 18 and 19 will effect a clockwise rotation of the leg 17 about the axis of the hinge 25 which connects such leg to the lower end of the stair section 13. A continued 55 movement of the rope or cable 20 will, therefore, ultimately move the stair section 13 and the leg 17 and links 18 and 19 into the dotted line position illustrated in Fig. 4.

Extending laterally from the staircase 12 and substantially chordwise of the tank 1 are partitions or baffle members 26 and 27. These baffle members include fixed sections 28 which extend for a distance of approximately one foot below the water level in the tank, as most clearly illustrated in Fig. 6. To the upper edge of the fixed sections 28 are hingedly secured plates 29, which with the sections 28, constitute the partitions 26 and 27. To the forward faces of the plates 28 are attached mirrors 30. Any suitable means (not shown) may be employed for the purpose of supporting the plates 29 and their associated mirrors 30 in any selected angular relation with respect to the fixed members 28 and the surface 70 of the water in the tank.

Positioned within the tank behind the partitions 26 and 27 are platforms 31 which provide a means of support for the performers at a level above the bottom of the tank. It may be noted at this point that for convenience, the depth of the tank may be approximately six feet; the depth of the water approximately five feet; and the platform 31 approximately one foot above the bottom of the tank. This results in there being about four feet of water over the platform 31 which permits a performer of normal height to stand on the platform 31 with his head above the level of the water.

The operation and mode of use of the above described apparatus whereby the objects of this invention may be attained will now be briefly described.

The performers will move into the pool either by diving from the springboards 10 or by walking down the inclined stairs 11. If the performers dive from the boards 10, the lower stair section 13 will be moved back into the dotted line position as illustrated in Fig. 4, so that they will not strike the stairs when diving.

If the performers move into the tank by walking down the stairs 11, then, the lower stair section 13 will be in the full line position as illustrated in Figs. 3 and 4.

After the performers have moved into the tank in either of the above defined manners, they will 105 then submerge and swim to the rear of the tank under the partitions 26 and 27. After passing under the partitions, the performers will move onto the platform 31, which is at such a height that the performers may stand thereon with their 110 heads above the level of the water. While in this position, the performers may effect a change of costume, if desired, or merely hesitate for a predetermined length of time before again swimming forward under the partitions 26 and 27 to 115 appear above the surface of the water in that portion of the tank which is exposed to the view of the audience. The performers may then rise out of the tank by means of the ladders 3 to repeat the disappearing act as many times as desired. 120

Should the tank 1 be supported at approximately the level of the audience, such audience may view the water within the tank by means of the mirrors 30 which are adjusted to the proper angle in order that this may be possible. The 125 adjustability of the mirrors with respect to the water level in the tank enables the apparatus to be set up for use regardless of any practical relationship of the audience with respect to the tank.

Should the performers desire to change costumes while standing on the platform 31, suitable racks may be provided at the rear of the tank within reach of the performers or an assistant whereby a plurality of costumes may be supported.

Should it be desired to have the performers disappear under the surface of the water in the forward portion of the tank without reappearing in the manner above explained, ladders may be provided adjacent the platforms 31 whereby the 140 performers may leave the tank.

Other modes of applying the principle of our invention may be employed instead of the one explained, change being made as regards the mechanism herein disclosed, provided the means 145 stated by any of the following claims or the equivalent of such stated means be employed.

We therefore particularly point out and distinctly claim as our invention:

1. In a device of the character described, the 150

- combination of a water filled tank and a partition extending transversely of said tank, said partition arranged with its lower edge below the water level in the tank and its upper edge a substantial distance above such water level. 5
2. In a device of the character described, the combination of a water filled tank, a partition extending transversely of said tank, said partition arranged with its lower edge below the water level in said tank and its upper edge a substantial distance above such water level, and a mirror supported in a substantially vertical position adjacent one side of said partition. 10
3. In a device of the character described, the combination of a water filled tank, a partition extending transversely of said tank, said partition arranged with its lower edge below the water level in said tank and its upper edge a substantial distance above such water level, and an inclined stairway comprising two relatively movable sections associated with said partition and extending adjacent the bottom of said tank, the lower section of said stairway lying below the water level in said tank being movably supported 25 whereby such lower section may be moved to a position adjacent the lower edge of said partition. 4. In a device of the character described, the combination of a water filled tank, a partition extending transversely of said tank, said partition arranged with its lower edge below the water level in said tank and its upper edge a substantial distance above such water level, and an inclined stairway associated with said partition and extending adjacent the bottom of said tank, the 30 lower section of said stairway lying below the water level in said tank being pivotally connected to that portion extending above the water level. 5. In a device of the character described, the combination of a water filled tank, a partition extending transversely of said tank, said partition arranged with its lower edge below the water level in said tank and its upper edge a substantial distance above such water level, an inclined stairway associated with said partition and extending adjacent the bottom of said tank, the lower section of said stairway lying below the water level in said tank being pivotally connected to that portion extending above the water level, and means for supporting 45 said lower stair section in alignment with the upper stair section. 6. In a device of the character described, the combination of a water filled tank, a partition extending transversely of said tank, said partition arranged with its lower edge below the water level in said tank and its upper edge a substantial distance above such water level, an inclined stairway associated with said partition and extending adjacent the bottom of said tank, the 50 lower section of said stairway lying below the water level in said tank being pivotally connected to that portion extending above the water level. 60
- ed to that portion extending above the water level, and a mirror supported in a substantially vertical position adjacent one side of said partition. 7. In a device of the character described, the combination of a water filled tank, a partition extending transversely of said tank, said partition arranged with its lower edge below the water level in said tank and its upper edge a substantial distance above such water level, a platform in said tank on one side of said partition and at a substantial distance above the floor of the tank. 80
8. In a device of the character described, the combination of a water filled tank, a partition extending transversely of said tank, said partition arranged with its lower edge below the water level in said tank and its upper edge a substantial distance above such water level, a platform in said tank on one side of said partition and at a substantial distance above the floor of the tank, and a mirror supported in a substantially vertical position adjacent one side of said partition. 85
9. In a device of the character described, the combination of a water filled tank, a partition extending transversely of said tank, said partition arranged with its lower edge below the water level in said tank and its upper edge a substantial distance above such water level, a platform in said tank on one side of said partition and at a substantial distance above the floor of the tank, and a mirror supported in a substantially vertical position adjacent one side of said partition. 90
10. In a device of the character described, the combination of a water filled cylindrical tank; an inclined stairway extending into said tank, the lower section of such stairway being pivotally connected to the upper section whereby such lower section may be selectively moved to either a substantially vertical position or into alignment with the upper section; means for supporting said lower section in said last-named position; vertical partition members extending 105 from said stairway laterally and substantially chord-wise of said tank, said partitions extending for only a short distance below the water level in said tank and for an appreciable distance above said water level; a platform in said tank above the bottom thereof and on one side only of said partitions, and mirrors supported in a substantially vertical position adjacent said partitions on the side opposite said platform. 110

LOTTIE MAYER WARFIELD. 115
